UNITED STATES PATENT OFFICE

MATTHEW J. DE FOREST, OF JACKSON HEIGHTS, NEW YORK, ASSIGNOR, BY MESNE ASSIGNMENTS, TO UNITED RESEARCH CORPORATION, OF LONG ISLAND CITY, NEW YORK, A CORPORATION OF DELAWARE

ELECTRICAL ATTENUATOR NETWORK

Application filed August 10, 1929. Serial No. 385,054.

This invention relates to apparatus for the phonographic recording of sound electrical-
ly, and more especially relates to improve-
ments in such apparatus wherein the sound
waves to be recorded are intercepted or picked
up by a plurality of sound translating de-
vices for microphones and conducted electric-
ally to a common recorder element.

An object of the invention is to provide at-
tenuating means for adjusting individually
the level of energy delivered from the vari-
ous sound translating devices to the recorder
element without disturbing the electrical im-
pedance relations existing either between each
input line and its respective attenuator, or be-
tween the output side of all attenuators and
the common recording circuit connected
thereto, whereby the impedances of such ele-
ments may be selected to reduce undesirable
reflection effects.

The above object is accomplished by em-
ploying, in each pickup circuit leading to the
recorder, an attenuator commonly designated
as a **T** network which has a plurality of im-
pedances in series in one side of the line, no
impedance in the other side of the line and a
shunt impedance. The impedances in series
in the line and the shunt impedance may be
varied conveniently by a single movable ele-
ment. These impedances are varied in steps
and have values, according to formula here-
inafter described, whereby the impedance
of each attenuator as viewed in opposite di-
rections, remains substantially constant for
various adjusted positions of the movable
member. The relation of the impedances of
the various elements is so chosen that the im-
pedance at the input side of each attenuator
substantially matches the impedance of the
line with its pickup or sound translating de-
vice therein and at the same time the com-
bined impedances at the output terminals of
all the attenuators substantially matches the
impedance of the common output circuit
which includes the recorder.

While this is not an essential feature of the
invention, the arrangement specifically de-
scribed hereafter makes it possible to vary
the attenuation from a maximum value down
to zero, thereby eliminating the dissipation
of energy in the attenuator at the minimum

setting such as occurs with the majority of
existing attenuator arrangements used for
this purpose.

A further object of the invention is to
reduce or prevent cross-talk between the vari-
ous recording or pickup lines which are con-
nected to the common recorder. This is ac-
complished with the arrangement above de-
scribed by directly connecting together the
sides of the respective lines which have no
attenuator impedance therein, whereby the
corresponding line sides of the individual re-
cording circuits are brought to substantially
the same potential whereby impedance un-
balance and cross-talk between these circuits
is substantially avoided.

Referring now to the drawings:

Fig. 1 shows an elementary **T** network, and
Fig. 2 an elementary **H** network such as it is
proposed to utilize in the attenuator arrange-
ment.

Fig. 3 shows an electrical recording circuit
utilizing two microphones each connected to
the input circuit of a recording element thru
variable **T** networks.

Fig. 4 shows a modification of Fig. 3 where-
in each microphone is connected to the input
circuit of the recording element thru a vari-
able **H** network.

Fig. 5 shows a circuit arrangement similar
to Fig. 3 but disclosing the essential structural
features of a **T** network attenuator adapted to
vary the attenuation in successive steps by
adjustment of a single control element.

Fig. 6 shows a modification of Fig. 5 where-
in each attenuator is variable continuously
between certain limits.

Referring to Fig. 1, the characteristic im-
pedance Z and the current attenuation K of
a **T** network are related to the resistance R_1
and R_2 in accordance with the following
formulae:

$$(1) \quad R_1 = Z \frac{K-1}{K+1}$$

$$(2) \quad R_2 = 2Z \frac{K}{K^2-1}$$

95

That is, if such a network be interposed be-
tween the two impedances of magnitude Z ,
it will introduce a current attenuation equal

100

to K therebetween. Furthermore, under such conditions the impedance looking in either direction from either pair of terminals of the network will be equal to Z irrespective of the amount of attenuation introduced thereby. In fact, if the attenuation K is sufficiently great, the impedance as seen from one pair of attenuator terminals will be Z regardless of the impedance connected across the opposite terminals thereof. It will be seen from the above formulae that by properly selecting the magnitudes of the resistances R_1 and R_2 any desired degree of attenuation may be obtained consistent with a preselected characteristic impedance value.

The H network of Fig. 2 is electrically the same as the T network of Fig. 1. The H network is obtained from the T network by distributing the resistance elements R_i equally between the upper and lower conductors as shown; i. e., each series arm equals

$$(3) \quad \frac{R_1}{2} = \frac{Z}{2} \cdot \frac{K-1}{K+1}$$

- 25 As a practical proposition it is desirable to utilize the T network where one side of the line is grounded, the H network being preferable where it is desired to ground the mid-point of the circuit.
- 30 Referring now to Fig. 3 which shows the application of the T network to an electrical pick-up and recording apparatus, two pick-up microphones are shown at 1 and 2 each connected in a local circuit containing a primary winding P_1 or P_2 of transformer T_1 or T_2 and a direct current supply source 3 or 4. The secondary winding S_1 of transformer T_1 is connected to a pair of terminals 5 of a variable T network 6, while the secondary winding S_2 of transformer T_2 is connected to a pair of terminals 7 of the variable T network 8. The output impedances of attenuators 6 and 8, respectively, are arranged in a closed series circuit which includes the primary winding P_3 of transformer P_3 by suitable connections extending between the pairs of terminals 9 and 35 and the winding P_3 .

50 The T networks 6 and 8 are shown in their generalized form each consisting of the variable series arms A and B and the shunt arm C interconnected by means of the sliding contacts D for adjusting the magnitudes of the arms. With the arrangement as shown each arm must be adjusted individually to its proper value although they may move in unison as shown in Fig. 5. The arms are so adjusted in accordance with Equations (1) and (2) as to obtain the desired attenuation while at the same time maintaining the characteristic impedance of the network at Z which is the impedance looking into the microphone circuits from the secondary transformer windings S_1 and S_2 , respectively. Thus each microphone, 1 or 2, 65 works into its proper impedance. Also by

making the impedance looking into the primary winding P_3 of transformer T_3 connected to the recording circuit equal to $2Z$, the combined impedances of the output circuits of the T networks 6 and 8 are connected to their proper impedance.

70 The secondary winding S_3 of transformer T_3 is connected to an amplifier 15, the output circuit of which is connected to the recording element comprising the electromagnet 10 operating on the pivoted armature 11 having associated therewith the cutting stylus 12 resting in operative relation upon a record 13 which in turn is suitably supported on a turn-table in the well known manner for recording purposes.

75 The level of energy delivered by microphone 2 to the amplifier 15 may be adjusted to a desired intensity by proper setting of the T network 8. Similarly, the energy delivered by microphone 1 to the amplifier may be adjusted independently of that delivered thereto by microphone 2 by a proper setting of the T network 6. Furthermore, as will be seen, the adjustment of the energy levels delivered by the various microphones is accomplished without disturbing the impedance relations existing between the various circuit elements. When the networks are set of zero attenuation, the series resistances A and B are short-circuited and the shunt arm C is on open circuit with the result that no attenuation is introduced in the circuit. This arrangement is in contrast with the methods of attenuation mentioned above wherein considerable energy is dissipated at the minimum attenuation setting.

80 Any number of sound receivers or microphones may be connected as indicated in Fig. 3 to a common input circuit. A separate attenuator is interposed between each microphone and the common input circuit for providing individual adjustment of the current delivered by the various microphones. The connection of the plurality of microphone circuits to the common input circuit may be accomplished in any desired manner, i. e., all the microphone circuits may be connected in series to the common input circuit, or all 95 may be connected in parallel thereto or a series-parallel arrangement may be utilized. In any case the impedance looking into the common input circuit should be made equal to the resultant impedance looking toward the microphones in order to avoid reflection losses.

100 It will be noted that each of the T networks 6 and 8 has no impedance in one side of their respective lines, i. e., between the right hand terminals 5 and 9 also between the left hand terminals 7 and 35, and that such line sides are directly connected together by the line connecting the right hand terminal 9 to the left hand terminal 35. This brings 115 the corresponding low impedance line sides 120

of each pickup circuit to the same potential whereby cross-talk between these circuits and which would otherwise be due to an unbalanced impedance to ground, is avoided.

5 Fig. 4 shows a circuit arrangement similar to that of Fig. 3 with the exception that the H networks 14 and 36 replace the T networks 6 and 8, respectively, of Fig. 3. The H networks comprise the equal series arms Y, E, 10 F and G, and the shunt arm H. For a desired attenuation and a given characteristic impedance, the various arms are adjusted in accordance with the relations expressed above in equations (2) and (3). The H networks 15 are shown in Fig. 4 in generalized form in that each series arm and the shunt arm must be individually adjusted to the desired value in each instance.

The attenuators disclosed in Figs. 3 and 20 4, while embodying the principles of the present invention, would not provide a very practical arrangement for adjusting the currents delivered by the various microphones since a number of careful adjustments would be 25 required on each attenuator to obtain a desired attenuation value. Fig. 5 shows a circuit arrangement similar electrically to Fig. 3, but utilizing T network attenuators of 30 efficient construction in that but a single adjustment is required for obtaining a selected attenuation value. The attenuators of Fig. 35 5 are arranged to vary the attenuation in successive steps, the change in attenuation between the successive steps being selected to meet the needs of a particular case. Figs. 5 and 6 illustrate an alternative connection with the low impedance side of one line connected to the high impedance side of the other line. The preferred connection is shown in Fig. 40 3 wherein the low impedance line sides are directly connected together as above described.

The attenuator 16 is interposed between the microphone 1 and transformer T_3 , while attenuator 17 is similarly interposed between microphone 2 and transformer T_3 , the transformers serving to adjust the apparent impedance. Each attenuator comprises a movable element 18 having rigidly affixed there- 45 to three conductively connected arms 19, 20 and 21, each arm being adapted to pass in succession over corresponding groups of contacts 22, 23 and 24 as the adjusting knob 25 is turned. Resistances L, M, N and O are 50 connected respectively between the successive contacts of group 23 and one of the input terminals 5, and similar resistances L, M, N and O are connected between the successive contacts of group 22 and one of the output terminals 9. Resistances R, S, T and U are 55 connected between the successive terminals of contact group 24 and the remaining input terminal 5 and output terminal 9. The contact arms 19 to 21, inclusive, are so positioned 60 relative to their groups of contacts that the

various arms make contact simultaneously with corresponding contacts of the respective groups 22 to 24, inclusive.

It will be seen that with the arrangement described a T network will be connected between the input and output pairs of terminals of an attenuator for each setting of the movable element 18, the resistances L, M, N and O constituting the successive pairs of series arms and resistances R, S, T and U 70 the corresponding shunt arms. The resistances of the series arms increase in the order L, M, N, O, while the resistances in the shunt arm decrease in the order R, S, T, U, being 75 suitably proportioned to maintain the characteristic impedance of the attenuator constant, while providing successively increasing steps of attenuation as the movable element 80 18 is rotated in a clockwise direction.

The attenuators are designed to vary the 85 attenuation from zero to a maximum value. Thus with attenuator 16 in the position shown, zero attenuation is introduced due to the fact that the resistance of the series arms L is zero, and the resistance of the corresponding shunt arm R is infinity since the circuit thru the shunt arm is indicated as being open. The movable element 18 of the attenuator 17 is shown in position for introducing maximum attenuation since the contact arms are on the top step connecting the large resistances O in the series arms and the small resistance U in the shunt arm. 90 95

The stops 26 and 27 are provided to set 100 the limits of rotation for the movable element 18. The successive contacts of the groups 22 to 24 may be numbered consecutively and a chart furnished showing the amount of attenuation introduced for each step, or the 105 amount of attenuation in suitable units, such as TU may be marked directly opposite the successive contacts. The resistances L, M, N and O are, of course, proportioned in accordance with equation (1) above, while the 110 resistances R, S, T and U are proportioned in accordance with equation (2), the desired degree of attenuation K for each step having been previously determined upon.

Attenuators of the type indicated at 115 16 and 17 are, of course, constructed rigorously in accordance with equations (1) and (2). The disadvantage of these attenuators, however, lies in the fact that the attenuation cannot be varied continuously between cer- 120 tain limits but must be varied in successive steps.

Fig. 6 shows a modification of the circuit of Fig. 5 wherein the attenuators shown within the rectangles 28 and 29, respectively, are 125 adapted to vary the attenuation continuously between certain limits. The advantages of the continuously variable attenuation, however, is obtained at the expense of some loss of accuracy and in the limitation upon the 130

range of attenuation values available as will be pointed out below.

The attenuators 28 and 29 are of the T network type and each comprises three slide wire rheostats I, J and K covering equal sectors of a circle. The movable element 18 is provided with a knob 25 for turning the same and has rigidly affixed thereto three sliding contacts 19, 20 and 21 set respectively at 120° to each other, each sliding contact being adapted to pass over a different one of the slide wire rheostats. The rheostats I and J constitute the series arms, while K constitutes the shunt arm of the attenuator. This is easily observable from the fact that with the movable element 18 set at any position a circuit is traced from the right terminal 5 of attenuator 28 thru a portion of rheostat I, sliding contact 19, sliding contact 20, thru a portion of rheostat J to the right terminal 9 of the attenuator. A path is also traced from the left terminal 5 and the left terminal 9 thru a portion of rheostat K and the sliding contact 20 to the midpoint between the series arms.

With the attenuators arranged in accordance with Fig. 6, the change in resistance of the series and shunt arms is in direct proportion to the angular setting of the movable element. Equations (1) and (2), of course, show that the shunt arm does not vary proportionally with the series arms so that the attenuators as constructed in Fig. 6 do not produce changes in attenuation rigorously in accordance with formulae (1) and (2).

As a practical proposition, however, it has been found that for an attenuator of this type constructed to vary the attenuation continuously over a relatively small range say from 2 to 20 TU, the amount of error introduced does not amount to more than ± 5 per cent. In order to construct an attenuator of this type having the attenuation values between 2 and 20 TU, it is necessary to properly locate stops 26 and 27 to prevent rotation of the movable element at proper points to set the limits of desired attenuation. Thus, for the minimum attenuation limit of 2 TU, there must be a small resistance L' in each of the series arms and a large resistance K in the shunt arm of the attenuator. Stop 26 is properly located to ensure this result as is shown for attenuator 29 which is set for minimum attenuation. If it were attempted to reduce the attenuation below 2 TU with the continuously variable attenuator, the error introduced would become excessive since for zero attenuation the shunt arm must necessarily have infinite impedance and it is, of course, obvious that the proper variation of the shunt arm between 2 TU and 0 TU could not easily be accomplished with the slide wire arrangement shown in Fig. 6.

At the position of maximum attenuation,

namely 20 TU, all of the resistances I and J should be in the series arms with but a small amount of resistance in the shunt arm. Stop 27 is suitably located to accomplish this result as shown for the attenuator 28 in which the movable element 18 is shown in the position of maximum attenuation which includes the small resistance M' in the shunt arm. In addition to properly locating the stops 26 and 27, the rheostat K must, of course, be properly positioned on the circle relative to the rheostats I and J after the fashion indicated in the drawings.

In order to determine the amount of attenuation introduced for each setting of the movable element 18, a scale 30 may be affixed to the frame of the attenuator and arm 19 equipped with a pointer 31 for indicating on the scale 30 as shown. The scale 30 may, of course, be properly marked to indicate the attenuation in accordance with a selected scale.

In a specific case for an attenuator constructed in accordance with Fig. 5, adapted to have a characteristic impedance of 200 ohms, and to introduce attenuations of 0, 10, 20 and 30 TU, the following values were required for the various resistance elements. For the series of arms: $L=0$, $M=103.8$, $N=163.6$, and $O=187.7$ ohms, respectively. The corresponding values for the shunt arms were: $R=\text{open circuit}$, $S=140.5$, $T=40.4$, and $U=12.7$ ohms, respectively.

For an attenuator constructed in accordance with Fig. 6 and having a characteristic impedance of 200 ohms, and arranged to introduce an attenuation varying from 2 to 20 TU, the series rheostats J and I were given a maximum resistance of 163 ohms each and the shunt arm rheostat K a maximum resistance of 859 ohms. The stop 26 was so located and the rheostat K so positioned relative to rheostats I and J that for the minimum, or 2 TU setting, the series arms contained 23 ohms each, while the shunt arm contained the maximum resistance of rheostat K, namely 859 ohms. For the maximum attenuation setting of 20 TU, the stop 27 was positioned to include all of rheostats J and I in the series arms, namely 163 ohms each, and only a portion of rheostat K amounting to 41 ohms in the shunt arm.

While the constant impedance networks have been disclosed specifically as applied in electrical pick-up apparatus for phonograph recording, the disclosure is, of course, not to be limited in such manner, but may be used in any instance where a plurality of energy sources are fed into a common circuit, and it is desired to provide individual adjustment of the currents delivered from the various sources of such input circuit. A further example of a case of this sort arises in the radio broadcasting of an orchestral selection where

a plurality of microphones are placed about the studio and the currents therefrom fed into a common amplifying circuit for transmission to the broadcasting equipment. Here again, it is desirable to provide individual adjustment of the currents from the various microphones in which case the **T** or **H** network attenuators of the type disclosed herein could be used for this purpose.

10 The attenuators of Figs. 5 and 6 need not be constructed specifically as shown in the drawings. For example, the rheostats **I**, **J** and **K** of Fig. 5 could be arranged in concentric circles of successively increasing diameters with the arms 19, 20 and 21 properly placed one above another for tapping off desired portions of their respective rheostats. Similarly, in Fig. 6 the contact groups 22, 23 and 24 could be arranged in concentric circles of increasing diameters and the contact arms placed one above another and each of sufficient length and being bent downward at its outer end to make contact with its proper group of contacts. Attenuators of the **H** network type may also be constructed in accordance with the principles set forth in Figs. 5 and 6.

30 The **T** or **H** networks need not necessarily have equal series arms such as is required for matching equal impedances as seen from its opposite terminals. Where the impedances between which the network is connected are different, unequal series arms would be required for suitably matching the impedances.

35 I claim:

1. In combination, a plurality of sound translating devices for producing electrical waves corresponding to sound waves, lines connecting said devices respectively to a common output circuit, a variable attenuator in each of said lines, each of said attenuators comprising a plurality of impedance elements in series in the line and an impedance element in shunt thereto, each of said attenuators having a single movable element for interposing in the corresponding line selected amounts of each impedance element for varying the energy transferred to said output circuit while substantially matching the impedance at the input terminal of each attenuator to the impedance of the line with its sound translating device therein, and while substantially matching the combined impedances at the output terminals of all said attenuators to the impedance of said output circuit.

60 2. In combination, a plurality of sound translating devices for producing electrical waves corresponding to sound waves, lines connecting said devices respectively to a common output circuit, a variable attenuator in each of said lines, each of said attenuators comprising a series of **T** networks, a single movable element for each attenuator for introducing in any one of a plurality of ad-

justed positions a **T** network comprising a plurality of impedances in one side of the line, substantially no impedance in the other side of the line, and an impedance in shunt to the line, and a direct connection between the respective sides of said lines in which said **T** networks have substantially no impedance. 70

3. In combination, a plurality of sound translating devices for producing electrical waves corresponding to sound waves, lines 75 connecting said devices respectively to a common output circuit, a variable attenuator in each of said lines, each of said attenuators comprising a series of **T** networks, a single movable element for each attenuator for introducing in any one of a plurality of adjusted positions a **T** network comprising a plurality of impedances in one side of the line, substantially no impedance in the other side of the line, and an impedance in shunt to the 80 line, the values of each of said **T** networks being so related to the impedances of the lines connected thereto that the impedance of each **T** network substantially matches at the input terminal thereof the impedance of the 85 line with its sound translating device, while also substantially matching the combined impedances of the output terminals of said attenuators to the impedance of said output circuit connected thereto, and a direct connection between the respective sides of said lines in which said **T** networks have substantially no impedance. 90

In testimony whereof I affix my signature.
